(57) CLAIM

I claim the ornamental design for a cigarette package, as shown and described.

DESCRIPTION

FIG. 1 shows a perspective view of the cigarette package, showing my new design;

FIG. 2 shows an expanded perspective view thereof;

FIG. 3 shows a left side view thereof;

FIG. 4 shows a top view thereof with the cover open;

FIG. 5 shows a front view thereof;

FIG. 6 shows a bottom view thereof;

FIG. 7 shows a right side view thereof; and,

FIG. 8 shows a back view thereof.

In the drawings the broken lines are for the purpose of illustrating portions of the cigarette package that form no part of the claimed design.
